UNITED STATES PATENT OFFICE

160,367

COMBINED SPICE HOLDER AND WALL SHELF

Carl A. Busch, Sandusky, Ohio

Application February 15, 1949, Serial No. 865

Term of patent 3½ years

(Cl. D33—3)

To all whom it may concern:

Be it known that I, Carl A. Busch, a citizen of the United States, residing at Sandusky, in the county of Erie and State of Ohio, have invented a new, original, and ornamental Design for a Combined Spice Holder and Wall Shelf, of which the following is a specification, reference being had to the accompanying drawing, forming a part hereof, in which:

Fig. 1 is a front perspective view of a combined spice holder and wall shelf, showing my new design.

Fig. 2 is an end perspective view of the article of Fig. 1.

Fig. 3 is a further perspective view of the article of Figs. 1 and 2.

I claim:

The ornamental design for a combined spice holder and wall shelf, substantially as shown.

CARL A. BUSCH.
